UNITED STATES PATENT OFFICE.

ISAAC B. RESOR, OF CINCINNATI, OHIO, ASSIGNOR TO WILLIAM RESOR & CO., OF SAME PLACE.

DESIGN FOR A HEATING-STOVE.

SPECIFICATION forming part of Design No. 17,354, dated May 24, 1887

Application filed April 5, 1887. Serial No. 233,794. Term of patent 7 years.

To all whom it may concern:

Be it known that I, ISAAC B. RESOR, a citizen of the United States, residing at Cincinnati, in the county of Hamilton, State of Ohio, have invented and produced a new and original Design for a Heating-Stove, of which the following is a specification, reference being had therein to the accompanying drawing.

My invention comprises certain new and original designs for the various castings of a heating-stove, one of these novel features being the foot, which is ornamented with a grotesque face, A, in relief, said face being that of a man with heavy mustaches, the ends of which develop into scrolls.

The second part of my invention includes the stove-base, consisting of a concave molding ornamented with a circle of arabesque scroll-work, B.

The third part of my invention includes the ornamented fret-work surrounding the fire-pot of a heating stove. This ornamentation consists of the interlaced bamboo canes and leaves, as seen at C.

The fourth part of my invention includes the Moorish ornaments D, forming a circle near the outer margin of the main top of a heating-stove.

The fifth part of my invention includes the upper portion of the main top, which is an ogee molding ornamented with a circle of oak-leaves and acorns connected by curved branches, all as shown at E.

The sixth part of my invention includes the swing-top of the stove, which top is a reverse ogee molding ornamented with a chaplet of oak-leaves, F, whose stems radiate from the center of said top.

The seventh feature of my invention consists in combining all the above-described ornaments in the castings for a heating-stove.

I claim as my invention—

1. The design for a stove-foot herein shown and described, the same consisting of a grotesque man's face, A, in relief, said face being provided with heavy mustaches, the ends of which develop into scrolls. 45

2. The design for a stove-base herein shown and described, the same consisting of a concave molding ornamented with a circle of arabesque scroll-work, B. 50

3. The design for a fret-work to surround the fire-pot of a heating-stove, herein shown and described, the same consisting of interlaced bamboo canes and leaves, as seen at C. 55

4. The design for the outer margin of the main top of a heating-stove, herein shown and described, the same consisting of the Moorish ornaments D, arranged in a circle. 60

5. The design for the upper portion of the main top of a heating-stove, herein shown and described, the same consisting of an ogee molding ornamented with a circle of oak-leaves and acorns connected by curved branches, as shown at E. 65

6. The design for the swing-top of a heating-stove, herein shown and described, the same consisting of a reverse ogee molding ornamented with a chaplet of oak-leaves, F, whose stems radiate from the center of said top. 70

7. The heating-stove design herein shown and described, the same consisting of the feet, ornamented as at A, the concave base, ornamented as at B, the fire-pot fret-work, ornamented as at C, the main top rim, ornamented as at D, the main top proper, ornamented as at E, and the swing-top, ornamented as at F. 75

In testimony whereof I affix my signature in presence of two witnesses.

ISAAC B. RESOR.

Witnesses:

JAMES H. LAYMAN,
SAM'L. S. CARPENTER.
